FRANZ AMRHEIN, OF SAN JOSE, COSTA RICA

QUICK RELEASEABLE KEY

Application filed May 27, 1929. Serial No. 366,393.

The invention relates to keys and has for its general object the provision of a key construction whereby the loop or handle of the key itself may be opened to permit ready engagement upon or disengagement from a key ring or the like.

It is well known that it is a more or less troublesome task to place a key upon a conventional type of key ring and to remove it if the occasion arises. It is also well known that it is frequently necessary to remove a key from a key ring and especially when use is made of the ordinary type of key ring which is divided circumferentially so that the key must be dragged about the entire key ring before it can be removed, this operation is troublesome, annoying and time consuming.

It is with the above facts in view that I have devised the present invention which has for an important object the provision of a key having a loop or handle with a releasable portion whereby its continuity may be interrupted to permit the loop or handle to be engaged upon or disengaged from a key ring with the utmost ease and simplicity.

Another object of the invention is to provide a key embodying this characteristic but yet at the same time so constructed that if desired it may be engaged upon a key ring in the ordinary manner with the quick releasable feature omitted or at least not used at that particular time, the selection of use depending upon the will of the person owning the key.

Another object of the invention is to provide a key in which there may be a movable section constructed in any one of a wide variety of specific ways depending upon which may be found the most advantageous in actual practice or which may be found preferable to the manufacturer.

An additional object is to provide a structure of this character which will be simple and inexpensive to make, easy to use, positive in action, efficient and rapid in action, durable in service, and a general improvement in the art.

With the above and other objects and advantages in view, the invention preferably

consists in the details of construction and the arrangement and combination of parts to be hereinafter more fully described and claimed, and illustrated in the accompanying drawings in which:—

55

Figure 1 is a side elevation of a key constructed in accordance with one embodiment of my invention.

Figure 2 is an edge elevation thereof.

Figure 3 is an elevation of a key of a modified form.

Figure 4 is an edge view thereof.

Referring more particularly to the drawings, and especially Figures 1 and 2, I have shown a key comprising the usual bit 10 formed upon a loop or handle 11. While a key of the Yale type is shown it should of course be understood that the invention is not in any way restricted to employment in connection with such a variety as it can be just as easily embodied in a key of a totally different type. In carrying out the invention the loop 11 is shown as interrupted at some point in its circumference, this being very readily effected by cutting away a portion. 70 This interrupted portion is indicated at 12 and is defined between a diagonal cut 13 and a pair of ears 14 located at opposite sides of a bifurcation as will be readily apparent, this bifurcation being shown by the dotted lines 75 15 in Figure 1.

Pivoted at 16 within this bifurcation between the ears 14 is a movable member or section 17 of such size and shape as to fill the opening 12 completely under normal circumstances. In other words, this member or section 17 has a diagonal end 18 intended to abut against the diagonal wall or shoulder 13 so that the movable section will be in effect a continuation of the remainder of the loop 11. A leaf spring 19 is preferably provided for normally holding this movable section in registration or circumferential alignment with the remainder of the loop and the spring may be anchored in any desired manner as 80 for instance by having one end fitted within and preferably soldered within a socket 20 at the juncture of the bit 10 with the handle loop 11.

Though it is not essential, I prefer to pro- 100

vide a rib or web 21 which traverses the handle loop 11 and which is preferably in alignment with the bit 10, the purpose being to divide the handle loop 11 into two parts, one 5 having the interrupted portion with the movable section therein and the other being continuous or unbroken.

In the use of this form of the invention, it is of course apparent that if the key is to 10 be left upon a key ring in the usual manner the uninterrupted portion of the handle loop is engaged with the key ring. If, however, it is desired to mount the key upon the key ring in such a way that it may be very quickly 15 and easily removed when such is desired, it is merely necessary to place the handle loop 11 against the key ring at the movable section 17 and then press sufficiently hard to overcome the resistance of the spring 19 where- 20 upon the key ring will enter the space within the loop. Removal is effected in the reverse manner and it is of course apparent that it is a very simple proposition.

As the invention is capable of embodiment 25 in various ways, I have shewn in Figures 3 and 4 a modification though the principle is identically the same. Referring to these two figures in detail, the key bit 21 is shown as formed at one end with a handle loop 22 in- 30 terrupted at some convenient point as shown at 23. At one end of this interruption or opening there is provided a socket 24 for a purpose to be described, and at the other end the loop 22 is of hollow formation or formed 35 with a socket 25 within which is slidably mounted an arcuate bar 26, or loop section normally urged toward the socket 24 by a coil spring 27 likewise mounted within the socket 25. The hollow or socketed portion 40 of the handle loop 22 is represented as formed with a circumferentially extending slot 28 along which travels a knob 29 on the movable section or bar 26, this knob being engageable by the thumb or finger nail of the operator 45 so that the section 26 may be slid along the socket 25 against the resistance of the spring 27 so as to expose the opening 23 and permit the handle loop to be engaged upon the key ring. This type of construction is very simi- 50 lar to the safety catches provided on the retaining rings of jewelry. In this form of the invention I preferably provide a bar or web 30 dividing the loop into sections in exactly the same manner and for the same purpose as 55 the web 21 in Figure 1.

In both forms of the invention it will therefore be apparent that I have provided a key of such construction that it may be engaged upon a key ring in the usual manner by di- 60 viding the key ring and sliding the key along, or by opening the movable section of the handle loop to permit ready engagement of the key upon the ring or removal therefrom by a simple lateral movement with respect there- 65 to. Both forms of the invention will operate

with equal efficiency and both will be of great advantage on account of the saving in time, labor and annoyance.

While I have shown and described two preferred embodiments of the invention, it 70 should of course be understood that I reserve the right to make all such changes in the details of construction and the arrangement and combination of parts as will not depart from the spirit of the invention or the scope of the 75 subjoined claim.

Having thus described the invention, I claim:—

A key comprising a one-piece substantially flat body portion, including a ring-like head, 80 a bar arranged centrally within the head and dividing the latter into two semicircular portions, one of which is uninterrupted, the other of said portions having an opening immediately adjacent the body of the key, a section pivoted at one end of the opening and adapted to normally close said opening to form a continuity of said semicircular portion, and a spring engaging said section to normally hold the latter within said opening. 85

In testimony whereof I affix my signature. 90
FRANZ AMRHEIN.
